UNITED STATES PATENT OFFICE

RALPH T. GANARY, OF BRIDGETON, NEW JERSEY, ASSIGNOR OF ONE-HALF TO EDWARD B. NEILL AND ANNA NEILL, BOTH OF FOX CHASE, PENNSYLVANIA

DESIGN FOR A GRIDDLE IRON

Application filed April 17, 1933. Serial No. 47,804. Term of patent 3½ years.

To all whom it may concern:

Be it known that I, RALPH T. GANARY, a citizen of the United States, residing at Bridgeton, in the county of Cumberland and State of New Jersey, have invented a new, original, and ornamental Design for a Griddle Iron, of which the following is a specification, reference being had to the accompanying drawing, forming part thereof.

In the drawing:

Figure 1 is a plan view of the article showing my new design; and

Figure 2 is a side elevation.

The dominant features of my design consist of a flat piece of metal of substantially uniform thickness, within the perimeter of which is a plurality of geometrical figures, said figures having alphabetical characters and animal figures therein.

I claim:

The ornamental design for a griddle iron, as shown and described.

RALPH T. GANARY.
